LIPSTICK GUARD

Charles Greenberger, New York, N. Y.

Substituted for abandoned application Serial No. 129,594, March 8, 1937. This application July 18, 1938, Serial No. 219,776

2 Claims. (Cl. 2—174)

This invention relates to new and useful improvements in a lipstick guard. This application is a refile of my original application, filed on March 8, 1937, Serial No. 129,594.

5 The invention has for an object the construction of a guard which is particularly intended to protect the lipstick on one's lips when trying on dresses and other garments which are slipped over the head.

10 These lipstick guards will be of exceptional value to retail stores since very often light colored garments are marred by prospective purchasers trying them on, and accidentally having portions of the garment come in contact with 15 the lips.

Still further the invention proposes to characterize the lipstick guard with a stiff element for extending over one's lips, and a stiff mouth member attached to the rear face of said element 20 for engaging between one's teeth to hold the guard over the lips.

The purpose of having the mouth element stiff is that it then does not give one a sagging sensation. If the mouth element is soft and mushy it 25 is highly objectional.

Another object of the invention is to construct the stiff sheet element to conform with the shape of one's lips.

Still further the invention proposes a lipstick 30 guard in which the stiff sheet element is sufficiently flexible to conform with the curvature of one's lips and in which the mouth member is releasably mounted on the sheet element so that the parts may be separated during transit and 35 storage. It is then possible to place the two small parts in small envelopes and supply them to users as required. They are then assembled and are ready for use.

Still further the invention proposes to arrange 40 the mouth member with a curved edge and to provide the holding means cooperative with the sheet member in a manner to force the sheet member against the curved edge and so produce the curvature necessary to fit one's lips.

45 For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

50 Fig. 1 is a perspective view of a lipstick guard constructed according to this invention.

Fig. 2 is a plan view of Fig. 1.

Fig. 3 is a transverse sectional view taken on the line 3—3 of Fig. 2 and showing the guard on a person's lips.

Fig. 4 is a perspective view similar to Fig. 1 5 but illustrating a modification of the invention.

Fig. 5 is a rear elevational view of a lipstick guard constructed according to a modification of the invention.

Fig. 6 is a plan view of Fig. 5. 10

The lipstick guard according to this invention comprises a stiff sheet element 10 for extending over one's lips and a mouth member 11 attached to the rear face of the element for engaging between one's teeth to hold the element over the 15 lips. The stiff element 10 is curved as shown in plan view (see Fig. 2) so as to conform with the curvature of one's face at the lip area. The mouth member 11 preferably should be of metal, Celluloid, or stiff plastic material. The covering 20 element 10 may be of similar materials.

In Fig. 4 a modification of the invention has been disclosed in which the sheet element 10^a has its edges curved to conform with the shape of one's lips. The mouth member 11 is also provided with a band 12 which may be of padding material so as not to hurt one's teeth. It may be a rubber band or cloth band, preferably suitably treated so as not to have an offensive taste. 25

In Figs. 5 and 6 another modification of the invention has been disclosed in which the lipstick guard comprises a flat flexible stiff sheet element 10^b attached to a mouth member 11^b. This mouth member has a curved edge 14 against which the flexible sheet 10^b is forced so that it assumes the 35 curvature of the edge 14. In Fig. 6 the dot and dash lines show the normal condition of the sheet element 10^b. The full lines show it held against the curved side 14. There are several headed studs 15 mounted upon the curved side 14 and 40 cooperative with bayonet slots 16 formed in the sheet element 10^b for holding the parts together. These bayonet slots 16 are arranged upon the circumference of a theoretical circle so that it is possible to turn the mouth member 10^b on a 45 theoretical center to disengage the parts.

When the sheet element 10^b is flat and the mouth member 11^b is disconnected from it they may be packed in small envelopes or other flat packaging material. It is only when they are to 50 be used that they are assembled.

While I have illustrated and described the preferred embodiments of my invention, it is to be understood that I do not limit myself to the precise constructions herein disclosed and the 55

right is reserved to all changes and modifications coming within the scope of the invention as defined in the appended claims.

Having thus described my invention, what I claim as new, and desire to secure by United States Letters Patent is:

- 5 1. A lipstick guard, comprising a flat flexible sheet element for extending over one's lips, a mouth member having a curved outer end, and means on the edge portion of said curved outer end which is adapted to engage said flat sheet and draw it against said curved outer end to curve said flat sheet so that it will conform with the contour of one's lips when said mouth member is inserted into one's mouth, said means, comprising fastening elements on the edge portion of said curved outer end which are adapted to engage complementary fastening elements on said flat flexible sheet element, said complementary fastening elements comprise bayonet openings in said flat sheet element and said fastening elements comprise headed studs which are adapted to engage said openings to fixedly hold said mouth member in position on said flat sheet element.
- 10
- 15
- 20

2. A lipstick guard, comprising a flat flexible sheet element for extending over one's lips, a mouth member having a curved outer end, and means on the edge portion of said curved outer end which is adapted to engage said flat sheet 5 and draw it against said curved outer end to curve said flat sheet so that it will conform with the contour of one's lips when said mouth member is inserted into one's mouth, said means, comprising fastening elements on the edge portion of 10 said curved outer end which are adapted to engage complementary fastening elements on said flat flexible sheet element, said complementary fastening elements comprise bayonet openings in said flat sheet element and said fastening elements comprise headed studs which are adapted to engage said openings to fixedly hold said mouth member in position on said flat sheet element, said bayonet openings being oppositely arranged on the circumference of a theoretical 15 circle so that it is possible to turn the mouth member on a theoretical circle to engage and disengage the headed studs in the openings.

CHARLES GREENBERGER.
